UNITED STATES PATENT OFFICE.

EDGAR GOODRICH, OF CHICAGO, ILLINOIS.

ARCH SUPPORT.

Application filed September 7, 1923. Serial No. 661,423.

To all whom it may concern:

Be it known that I, EDGAR GOODRICH, a citizen of the United States, residing at Chicago, in the county of Cook and State 5 of Illinois, have invented new and useful Improvements in Arch Supports, of which the following is a specification.

This invention relates to orthopedic apparatus, and has special reference to an arch support to be worn in a shoe for the purpose of supporting arches in such troubles as cases of flat feet, fallen arches and the like, as well as to aid in strengthening the weak arches.

15 Heretofore it has been customary to make arch supporters of this character with the portion beneath the internal part of the arch thicker than the portion beneath the external part, the idea being in such cases to raise 20 the hollow part of the arch.

Arch supporters constructed in this manner tend to force the middle of the foot outward, and in place of properly elevating the arch, they have a tendency to distort the 25 foot laterally.

The principal and most important object of the present invention is to provide an arch supporter wherein the internal portion of the arch will be left more or less free, while the external portion will be raised and thereby the foot will be prevented from having 30 its central portion distorted outwardly.

With the above and other objects in view, the invention consists in general of an arch 35 supporter so designed and constructed as to raise the external portion of the foot arch without tending to shove the arch laterally.

In the accompanying drawings like characters of reference indicate like parts in the 40 several views, and:

Fig. 1 is a bottom plan view of the improved arch supporter.

Fig. 2 is a section on the line 2—2 of Fig. 1.

Fig. 3 is a section on the line 3—3 of Fig. 1.

In forming this arch supporter there is taken a strip or sheet of material, such as leather or the like, and the body of the arch supporter is formed from this strip of material by cutting the same to the contour of the rear inner portion of the shoe, the forward end of the strip terminating at the point in the shoe where the phalanges begin so that this portion of the foot is

left free. Such a body is indicated is general at 10, and it is to be observed that this body has its edges bevelled all around as at 11 except at the external arch portion 12, it being understood that Fig. 1 is a 60 bottom plan view of the arch supporter for the left foot, and that the arch supporter for the right foot is complementary thereto. Thus the body is left thicker at the external arch portion than at the internal arch portion. Furthermore, there is secured beneath the external arch portion a strip of similar material to the body, the leather being preferred, as shown at 13, and this strip tapers from its center front and back 65 to a sharp edge, as can be seen in Fig. 3.

It is also preferred to position between the strip 13 and the body 10 a stiffening member 14, which may be of any suitable material, either metallic or non-metallic as 70 the particular case may require.

Now it will be observed that an arch supporter constructed in accordance with this invention will, when in use, elevate the external portion of the arch where it normally rests upon the ground in standing, and this without crowding the same to one side or the other. Thus by positioning this thickened member beneath the external portion of the arch an entirely different and 80 superior effect is obtained from an arch supporter wherein the interior portion of the supporter is thickened.

There has thus been provided a very simple and efficient device of the kind described and for the purpose specified.

Having thus described the invention, what is claimed as new, is:

An arch support consisting of a body formed from a sheet of material shaped to 95 conform to the plantar surface of the foot posterior to the tarsal portion whereby to leave the tarsal portion free, said material being gradually thinned at all of its periphery except at the portion beneath the 100 exterior arch portion of the foot, a narrow strip of similar material tapering in thickness from the middle to each end located beneath the exterior arch portion of the body, and secured thereto, and a reinforcing 105 and stiffening strip between the narrow strip and the body.

In testimony whereof I affix my signature.

EDGAR GOODRICH.
